M. DONALDSON,
UNDERGARMENT,
APPLICATION FILED SEPT. 27, 1920.

1,407,390.

Patented Feb. 21, 1922.

UNITED STATES PATENT OFFICE.

MARGARET DONALDSON, OF PARIS, KENTUCKY.

UNDERGARMENT.

1,407,390.

Specification of Letters Patent. Patented Feb. 21, 1923.

Application filed September 27, 1920. Serial No. 412,945.

To all whom it may concern:

Be it known that I, MARGARET DONALDSON, a citizen of the United States, residing at Paris, in the county of Bourbon and State 5 of Kentucky, have invented certain new and useful Improvements in Undergarments, of which the following is a specification, reference being had to the accompanying drawings.

10 It is the purpose of the present invention to provide a garment, which, though especially designed for children, may be constructed for grown persons, there being means stitched to the garment and passing 15 over the shoulders and intersecting at the rear slightly below and adjacent the shoulder blades, for reinforcing the waist portion of the garment, and more readily supporting the bloomers comfortably on the wearer.

20 It is a further purpose to construct the crotch of the bloomers, so as to prevent binding, cutting or rubbing, or pressure on the groin, or on the legs of the wearer.

A still further purpose is to so shape the 25 connected parts of a transverse seam of the crotch of the bloomers, and so curve the connected edges and to form a dart in the center of the forward edge portion of the front section of the garment, so as to cause the garment to remain forward of and out of contact with the body of the wearer, hence preventing binding, cutting or rubbing to the wearer.

In order to cause the forward section or 35 part of the garment to spring forward and remain forward from the body of the wearer, the edge of the front section which is connected to the back piece of the garment by a felled seam, is rounded, as clearly shown, 40 and is provided with a dart. It is to be found that by so constructing the front section of part of the garment does not render the front of the bloomers longer than the back, because the leg length to the waist is 45 the same as ordinary bloomers.

While the design and construction at present illustrated and set forth is deemed preferable, it is obvious that as a result of a reduction of the invention to a more practical form for commercial purposes, the invention may be susceptible of changes, and

the right to these changes is claimed, provided they are comprehended within the scope of what is claimed.

The invention comprises further features 55 and combination of parts, as will be herein-after set forth, shown in the drawings and claimed.

In the drawings:

Figure 1 is a view in perspective showing 60 the improved garment as applied to the body of the wearer, showing the shoulder bands stitched to the body of the garment.

Figure 2 is a perspective view of the garment showing the rear thereof.

Figure 3 discloses collective views, illustrating the fact that the body of the bloomers are separable, the latter being capable of attachment to the former.

Figure 4 is a perspective view of the lower 70 part of the garment, showing the crotch thereof.

Figure 5 discloses collective views showing the lower parts of the front and rear pieces of the garment, showing the curvatures of the edges of the crotch portion.

Referring more especially to the drawings, 1 designates the waist or body of the garment, which comprises the two front portions 2 and the back piece 3. The back piece 80 fits the back of the wearer and has portions adjacent the sides extending forwardly substantially half way the sides of the body of the wearer. The front parts of the garment have their remote portions extending rear- 85 wardly substantially one-half the sides of the body of the wearer, and are united or stitched by means of seams with the forwardly extending parts of the back piece. These seams 4 are turned and stitched, so as 90 to produce a neat appearance from the interior and exterior of the garment. The front pieces 2 extend upwardly a half way from the shoulder and are provided with buttons or other fasteners 5, to engage but- 95 ton holes or other means of the extensions 7 of the back piece. The extended parts of the front pieces 2 and the extensions 7 constitute shoulder straps. Snap fasteners may be used instead of buttons, for connecting 100 the shoulder pieces of the front and back parts of the garment. The front pieces of

the garment are reinforced by the strips or straps 8 which are stitched at 9 to the front piece of the waist of the garment and arranged along the extended parts 2 of the 5 front pieces. The back piece is also reinforced by the straps 10, which are stitched to the garment as at 11. These straps 10 intersect each other and are stitched at the intersection, and extend from the waist line to 10 the terminals of the parts of the back piece, which extend over the shoulders of the wearer. The button holes are formed through these reinforcing straps. By this construction of the waist or body portion of the garment 15 the shoulder receiving openings are formed, and the edges of these openings are provided with a binding 12. Also the neck receiving opening is formed, and the edges of this opening are likewise provided with 20 a binding, which merges into the overlapping parts of the front of the garment.

In Figures 1 and 2 the garment is provided with a waist band or strap 15, which is stitched to the garment.

25 The bloomers comprise the front and back pieces 16 and 17. The side edges of the front and back pieces are connected by means of felt-seams 18. The upper edge of the front piece of the garment is connected 30 to the waist or body of the garment by means of the stitches and the waist band or strap 15. In other words the upper edge portion of the front piece of the bloomers is interposed between the waist band or strap 35 and the material of the front part of the body of the garment, after which the parts are stitched together. The seams 18 at the sides of the bloomers terminate a short distance from the waist band of the body of 40 the garment thereby affording openings. The upper edge of the back piece of the bloomers is connected to the waist band of the body of the garment detachably, by buttons 20 as shown, or by any other suitable 45 fastening means, such as snap fasteners (not shown). The forward part of the waist band is provided with loops 21, to which buttons 22 are connected, for attachment of other garments. The waist is also supplied 50 with extensions 23 having eyelets 24, adapted to receive safety pins or the like, whereby other wearing apparel may be connected thereto.

55 The front piece of the bloomers is provided with an enlarged curved arch portion, the rounded transverse edge of which is rearwardly extended, and is connected to the edge 25 of the back piece of the bloomers, by means of a felled-seam 26. Before stitching 60 the curved edge of the arch of the front piece, the front piece is constructed with a V-shaped dart 28^a, the edges 27 of which are stitched together as shown at 28, and by this construction a curvature of the arch of 65 the transverse edge of the front piece of the

garment, causes the front part of the garment or bloomers to bulge or swing forwardly, and remain out of contact with the body of the wearer, thereby avoiding binding, cutting or rubbing the body. The front piece 70 of the bloomers has a forward opening 29 provided with buttons or other fasteners 30, whereby the edges of the opening may be readily connected. In the drawing there is also disclosed bloomers separate from the 75 body of the garment, but capable of attachable connection to the body of the garment, whereby in this way the garment may be termed a union suit. If desired the legs of the garment may be extended longer than 80 that shown, and in this case provided with draw strings or elastic bands, whereby when the garment is worn, it will appear as though the person is wearing petti-bockers. When the legs of the garment are short, they 85 may or may not have draw strings or elastic bands, as the case may be.

The invention having been set forth, what is claimed as being useful is.

1. In a garment as set forth, a body section, a section for the reception of the legs, the leg receiving section comprising front and back pieces provided with angular crotch portions, the transverse edge of the crotch portion of the front piece being arcuately shaped, the transverse edge of the crotch portion of the back piece being straight, said crotch portions being connected, the construction and arrangement of the transverse edges of both crotch portions being such as to cause the front piece to bulge forwardly from the body. 90

2. In a garment as set forth, a bloomer section for the reception of the legs of a wearer, comprising front and back pieces, 105 having broad angular crotch portions connected together, the transverse connecting edge portion of the crotch of the front piece being arcuately shaped, the construction and arrangement of which and the transverse 110 edge portion of the crotch of the back piece being such as to bulge the front piece forwardly from the body, and means arranged adjacent substantially the central portion of the transverse edge of the crotch of the front piece and constructed to insure bulging of the front piece from the pelvis bone of the wearer. 115

3. In a garment as set forth, a section for the reception of the legs of the wearer, comprising front and back pieces provided with broad transverse angular crotch portions fastened together, the transverse edge of the crotch portion of the front piece being arcuately shaped, the corresponding edge portion of the crotch portion of the back piece being straight, the construction and arrangement of said connected transverse edge portions of both crotches being such as to cause the front piece to bulge forwardly 120

125

130

from the body, the front piece having a dart arranged adjacent the transverse angular crotch substantially centrally of the arcuately shaped edge portion, thereby insuring bulging of the front piece, said garment including a body section having shoulder straps detachably connecting to the shoulders, and reinforcing straps carried by the front and rear of the body section and extending over said shoulder straps for reinforcing the same. 10

In testimony whereof I hereunto affix my signature.

MARGARET DONALDSON.
